JOHN W. BARTLETT AND DAVID P. BOSWORTH, OF HARMAR, OHIO

Letters Patent No. 94,544, dated September 7, 1869.

IMPROVED MACHINE FOR MAKING RAILROAD-SPIKES.

The Schedule referred to in these Letters Patent and making part of the same.

To all whom it may concern:

Be it known that we, JOHN W. BARTLETT and DAVID P. BOSWORTH, of Harmar, in the county of Washington, and State of Ohio, have invented a new and useful Improvement in Machines for Making Railroad-Spikes, Bolts, Rivets, &c.; and we do hereby declare that the following is a full, clear, and exact description of the same, reference being had to the annexed drawings, making part of this specification, in which—

Figure 1 is a front elevation of the machine, showing the driving-shaft, pulley, balance-wheel, and the operating-parts for forming the spikes and other articles to be made therewith;

Figure 2 is a vertical sectional elevation, on line x of fig. 1;

Figure 3 is a vertical sectional elevation, on line y of fig. 1;

Figure 4 is an end view, showing the driving-pulley, and the cam and rod which move the outer end of the heading-lever;

Figure 5 is a side elevation of the lever which is to be used in making bolts and rivets; and

Figure 6, an end view of the bolt-heading lever.

Figure 7 is a front elevation of the dies for forming the spikes, showing also the shear or knife for cutting the same from the bar, and the guide for guiding such bar to the knife;

Figure 8 is a plan and sectional elevation of a pair of dies for forming the heads of bolts;

Figure 9 is a plan and sectional elevation of a pair of dies for forming the heads of rivets;

Figure 10 is a side view of a spike, as it appears after having been formed in the machine, it having the outer surface of its head rounded;

Figure 11 is a side elevation of a spike, with the outer surface of its head bevelled from its centre toward its edges;

Figure 12 is a section on line 1 1 of fig. 10;

Figure 13 is a section on line 2 2 of fig. 11;

Figure 14 is an end view of the dies for holding the spikes; and

Figure 15 is a front elevation of the knife which cuts the part to be transformed into a spike from the bar.

Corresponding letters refer to corresponding parts in the several figures.

This invention relates to machines for forming spikes, bolts, rivets, and other similar devices; and

It consists in the combination and arrangement of its parts, for forming spikes and bolts partly by swaging and partly by pressure produced by an eccentric or cam, or their equivalents, as will be more fully explained hereinafter.

The invention further consists in the combination and arrangement of the remaining portions of the machine, as will be set forth.

A, in the drawings, represents the frame or table of the machine, which may be of any desired area of sur-

face, and of suitable thickness to give it the required strength.

From the table A project four standards, A¹ A² A³ A⁴, three of which extend upward for a distance sufficient to enable them to receive and support the driving-shaft B, and the guides for the upper ends of the eccentric-rods C, C¹, C², and C³, which have their upper ends secured in the cap upon the top of these standards.

B represents a shaft, which has its bearings in the standards above alluded to, at some distance from their upper ends.

To one of the outer ends of this shaft there is to be secured a fly or balance-wheel, B¹, for the purpose of steadyng the motion of the operating parts of the machine.

Upon the opposite outer end of this shaft is a pulley or band-wheel, over which the belt passes which drives the machine, while upon the intermediate portion of the same shaft there are secured four eccentrics or cams, one of which is lettered B², and is outside of the frame, but inside of the driving-pulley, while the others, B³, B⁴, and B⁵, are located between the outer standards of the frame. The office of these eccentrics or cams is to give motion to the different parts of the machine, as will be more fully described hereinafter.

C represents an eccentric-rod, which works in suitable guides, secured to the standard A¹, its upper end being provided with a strap, which encircles eccentric B², while its lower end is provided with a slot, which receives the outer end of lever H, for the purpose of giving a reciprocating movement to such lever.

C¹ represents an eccentric-rod, which has formed upon it a yoke, at the point where the shaft B passes through it. This yoke is of the proper dimensions to receive the eccentric B⁴, and is so arranged, with reference thereto, that as the shaft B is rotated, the said eccentric will give a vertical movement to said rod, the lower end of which works in suitable guides, formed upon or secured to the inner face of standard A¹. Upon the lower portion of this rod, and upon its inner face, there are to be formed two inclined planes or segments of circles, which form a track to control the movements of swinging arm F, for a purpose soon to be described.

C² represents an eccentric-rod, similar in all respects to the one last above described, except that it has upon its lower portion a rectangular formation, C⁵, its greatest surfaces being those which are toward the front and rear of the machine, while its edges, or parts of least surface, are toward the standards, against which they bear, and upon which they slide, they being held in their positions by means of suitable plates of metal screwed to such standards. To the front side of the rectangular portion of rod C² there is to be pivoted a swinging arm, F, as shown in fig. 1.

C³ represents a cam-rod, which is located between

the standards A^2 and A^3 , its upper end being guided by the bearing formed in the cap A^5 , as in the cases previously described, while its central portion, or that which surrounds the shaft B , is formed as shown in fig. 2, in order that the cam B^6 may give to the rod a rapid movement, at the proper time for opening the dies to permit the spike which has been formed to be displaced, and also to permit the bar from which the spikes are cut to be moved forward.

Upon the lower portion of this yoke, and upon its outer side, there is to be a projection, which, upon its upper surface, is to be in the form of a segment of a circle, which is for the purpose of allowing the projection upon the side of cam B^6 to act upon the rod, to force it down upon the spike after the force of the spring which acts to give the blow has been expended, which operation will hereafter be described.

That portion of this rod which is below the yoke may be rectangular, or of any other suitable form, to work in guides formed in or upon the standards A^2 and A^3 , it having suitable plates for holding it in position attached to such standards. To the extreme lower end of this rod there is to be attached the upper half of the die D , which forms the spike or bolt. This upper die may be cast upon, or otherwise secured to the rod, and is to have, in its lower surface, a recess corresponding to one-half of the spike or bolt to be formed therein. Upon the outer end of this die there is to be secured a shear or knife, the inner edges of which shall be in a line with, and move down upon the outer end of the lower die, so that when the upper die comes down, this knife shall be brought in contact with the bar from which the blanks are to be cut, and cut such blanks from such bar which lies upon the tables of the machine.

D represents the upper die, above referred to, its construction and arrangement being shown in figs. 1, 7, and 14.

D^1 represents the lower half of the die, the upper face of which is to have a recess in it, similar in form to the one in the lower face of the upper one, while upon the vertical face of its inner end there is to be formed a cavity, as shown in figs. 7 and 14, in which the head of the spike is to be formed. This die is to be secured in a projection formed upon the bed of the machine.

D^2 represents the shear or knife, above referred to, it being shown as secured to the upper half of the die by means of screw-bolts, by which it is made adjustable.

D^3 represents that portion of the table, or an attachment thereto, having the pins in it to guide the bar to the cutter.

D^4 represents a spring which is to be attached to the standard A^3 , in such a manner that it shall press upon the bar to be operated on during the action of the cutter, but that as the die D is raised, it shall come in contact therewith and raise it up, so that its vertical portion shall be raised off from the bar from which the blanks are to be cut, so that the attendant may shove such bar forward while the die is in its elevated position preparatory to its being cut and swaged upon the downward movement of the die.

E represents a star-wheel, which has its bearings in ears which project from the bed of the machine, in such a manner that when the wheel is in position, its arms shall work in a slot cut through the lower die about midway of its lower length. The office of this wheel is to remove the spike from the lower die after it has been formed. To enable it to perform this function, it is provided with a series of arms, upon the outer ends of which there are to be formed hook-shaped projections, which, in the rotation of the wheel,

come in contact with the rear surface of the spike, as it lies in the die.

E^1 represents a spring, which is to be secured to the under side of the bed A of the machine, and be curved downward, so that the outer ends of the arms of the wheel E may rest therein, and bear upon it, for the purpose of preventing the wheel from turning at the wrong time, or from turning too far, when it is moved by the spring-hook E^2 , which is to be secured to the lower surface of the upper die, so that as this die is moved upward, it shall catch upon one of the arms of wheel E , and bring it into the position shown in fig. 2, in which position it is ready to discharge a spike at the next upward movement of the die.

F represents a right-angled arm, which is to be pivoted to the rectangular portion of the eccentric-rod C^2 . The lower or horizontal portion of this arm, is to be slotted to receive two friction-rollers—one, F^2 , upon its outer end, and one, F^1 , at the point where the horizontal portion diverges from the vertical portion. The roller F^2 of this arm, in conjunction with the inclined surfaces of the reciprocating rod C^1 , is designed to regulate the position of the arm and its roller, F^1 , with reference to the head of the spike and the dies D D^1 ; its arrangement, and that of the eccentrics or cams on shaft B , being such, that as the upper die is raised, to permit the bar from which the blanks are to be cut, to be pushed forward until it strikes the adjustable stop F^3 which is secured to the lower portion of arm F , the rod which has the arm F attached to it, shall be moved up also, so that as the die falls, and cuts the bar, and leaves a blank in the dies, a continuous movement of the driving-shaft in the same direction shall cause the arm to descend and bend that portion of the blank which projects beyond the inner surface of the dies downward at a right angle, at which time the eccentric, B^3 , brings the lower inclined or segmental surface of rod C^1 in contact with roller F^2 , and keeps it in contact with the portion to be bent, when, in consequence of a further movement of the shaft, the arm and its rod will be raised, and the roller F^1 will be carried upward before the die commences to rise, and any surplus of iron that may remain upon the head of the spike will be carried upward, and the upper edge or arm of the spike will be made square, or nearly so, with reference to its upper surface, which latter effect will be produced by means of the upper inclined surface of the rod C^1 coming in contact with roller F^2 , and thus keeping roller F^1 in contact with the head of the spike during the upward movement of the arm and the rod to which it is attached. As soon as the operation above described has been performed, the die commences to rise, and thus the operation is repeated as often as is practicable.

G represents a spring, which in this instance is secured to the cap A^5 of the frame, it being of a bent or curved form, and so arranged that its outer end shall rest upon the top of the rod to which the upper or movable die is attached, in order that as such rod is carried upward by its eccentric, the tension of the spring will be affected, and so soon as the arm B^6 has passed the point of the yoke upon which it bears, to cause such upward movement, the spring will act to drive the die down upon the blank with great force, and thus perform the swaging-part of the operation, after which, and before the spike has been removed from the dies, the cam or projection upon the side of B^6 comes in contact with the shoulder or projection upon rod C^1 , and presses the die down upon the spike, and thus the operation of forming the spike or bolt is completed. The arrangement of these parts is such, that if the point of the spike is completed by the stroke of the movable die, and the surfaces of the dies come in con-

tact with each other, then projection of cam B^6 does not come in contact with the projection upon rod C^3 , and consequently no pressure will be applied to the die.

H represents a lever, which, in making bolts and rivets, is to be used in place of the arm F , it being pivoted to a projection upon the under side of table A , and so arranged that its outer end shall enter the slot in the lower end of eccentric-rod C , so that as said rod is carried upward by its eccentric, the die which is placed in the short arm of the lever, shall come in contact with that portion of the blank which protrudes through the stationary die, and upset and form a bed upon the same. In order that dies of different forms may be used for different kinds of work, it is, of course, necessary that they, and the parts to which they are attached, should be so constructed that one set of dies may be removed, and another set substituted in place thereof. When used for heading bolts and rivets, the rod C^4 and arm F are to be removed, so as to permit the arm of lever H to pass into its slot in rod C .

I I' represent a pair of dies, which are to be used in heading bolts; the one having the cavity in its face, being inserted into the end of lever H for forming the head of the bolt, while the other one is to be inserted into a projection which should be formed upon table A in such a manner that the rod may pass through it as described in making spikes.

I' I' represent a set of dies to be used in making rivets, which are to be arranged in all respects as are those above described for making bolts.

It will be apparent that this machine may be used in a horizontal position if preferred, and also that various arrangements of the spring may be adopted, other than that shown, if desired. It will be seen, also, that the lever H may be used for heading spikes by changing the fulcrum so as to give the bevelled form to the head thereof, for which purpose different holes are provided in said lever.

Having thus described our invention.

What we claim, and desire to secure by Letters Patent, is—

1. The combination of the swaging-dies D D^1 , and reciprocating pawl E^2 , with the discharging-wheel E , respectively constructed and arranged in relation to each other substantially as set forth.

2. The combination of mechanism for operating the movable swage D , constructed and operating substantially as described, so as to operate the movable die, first by percussion and then by compression.

3. The combination of the dies D D^1 , with the reciprocating header F^1 and gauge F^3 , substantially as and for the purpose set forth.

4. The combination of the reciprocating plunger C^5 , elbow-lever F , and heading-roll F^1 , constructed and arranged, in relation to the dies, substantially as described, with mechanism which shall cause such heading-roll, F^1 , in its reciprocations, to bear upon and traverse twice along the head of the spike, substantially as and for the purpose set forth.

5. The combination of the roller F^1 , oscillating arm F , eccentric-rod C^2 , and reciprocating track C^4 , so arranged in relation to each other as to operate substantially as and for the purpose set forth.

6. The combination, substantially as described, of the following elements, viz., dies to form the shank of the spike, a header reciprocating in a line perpendicular to the axis of the spike, and a discharging-wheel, all operated by eccentrics or cams, substantially as set forth.

7. The combination of the lever H , rod C , and eccentric B^3 , arranged to operate substantially as and for the purpose set forth.

In testimony whereof, we have signed our names to this specification, in the presence of two subscribing witnesses.

J. W. BARTLETT.
D. P. BOSWORTH.
